UNITED STATES PATENT OFFICE.

JAMES B. MONAHAN, OF NEW YORK, N. Y., ASSIGNOR TO LITHO ETCHING CORPORATION, OF NEW YORK, N. Y., A CORPORATION OF NEW YORK.

SAFETY DEVICE.

Application filed July 29, 1925. Serial No. 46,755.

This invention relates generally to safety devices for a press or the like; and has for its main object and feature the production of means whereby the press cannot, in case 5 the operator keeps his foot on the treadle, repeat its cycle of operations, unless, at the same time, both hands of the operator are outside the zone of danger.

In the accompanying drawings the invention is disclosed in a concrete and preferred form.

Fig. 1 is a general view of a punching press or the like with the device of the invention shown in position.

Fig. 2 is a fragmentary view of the framework of the machine showing the two push buttons for establishing a circuit to latch the connection from the foot treadle.

Fig. 3 is a sectional plan view on the plane 20 of line 3-3 of Fig. 4.

Fig. 4 is a vertical sectional view on the plane of line 4-4 of Fig. 3.

Fig. 5 is a diagram showing the electrical connection.

1 is a punching press, or the like, in which member 2 drops, or is otherwise actuated as by cam means, when a clutch is thrown in by merely controlling rod 3 by means of foot treadle or actuating means 4 all in a manner 30 well understood.

Controlling rod 3 consists of two members 5 and 6, one of which, in this case 6, is provided with a casing 7; and one of which, in this case 5, is provided with a latching member 8 that extends into the casing. There is a complementary latching member, within the casing, consisting here of two jaws 9 pivotally supported at 10. Suitable means such as armature 11, pivoted at 12, is provided whereby, when magnet 13 is energized, 40 said jaws are brought against and close around latch 8 so that, when the treadle is depressed, member 6, acting through the latch members, will pull down member 5 and release the clutch of the press. The means 45 preferably used to energize magnet 13 is an electric circuit 14 controlled by two push buttons 15 on the framework, both of which must be actuated to close the circuit and 50 which are so spaced that the operator must use both hands and thus keep the latter out of the danger zone.

The character of the machine to which this attachment is applied is preferably such that

when the machine is started it goes through 55 a cycle of operations and then stops. It will be understood, however, that, ordinarily, if the operator keeps his foot on the treadle and thus in active position, the press will repeat its cycle of operations indefinitely. 60 This cannot occur with the present construction, unless at the same time both push buttons are in, in which case no injury can be 65 sustained by the operator; and it will be observed, that should the operator absent-mindedly remove one or both hands from the push buttons, the magnet will become de-energized and therefore cam 16 on latch 8 will spread the jaws apart when it rises under compulsion of the automatic throw-out clutch of the press and consequently the press will stop even though the treadle remains depressed. When, after latch member 8 has risen out of the casing, the operator removes his foot from the treadle, said 70 cam 16, having two faces, will, if the circuit has accidentally been closed, separate the jaws when it again enters the casing. Armat- 75 ure 11 falls by gravity into the position indicated in Fig. 3 so that whenever the circuit is broken there is nothing to compel the jaws to remain in their closed position. It follows: therefore, that when the circuit is broken and the treadle depressed, member 6 will move downwardly but member 5 will 80 remain stationary and the press will not operate.

In case it is desired for any reason to render the safety device inactive, an authorized person may insert key 17 and turn 90 locking member 18 which will keep the armature in a position where the jaws will remain closed.

I claim:

1. A safety device for a machine of the 95 character set forth including: a connecting rod consisting of two members, an actuating device for one of said members, a cas- 100 ing carried by one of said members, a latch engaging member on the other of said mem- bers to enter the casing, a complementary latching member within the casing, and means extraneous of the casing to control engagement of said latching members.

2. A safety device for a machine of the 105 character set forth including: a connecting rod consisting of two members, an actuating device for one of said members, a cas-

- ing carried by one said members, a latch engaging member on the other of said members to enter the casing, a complementary latching member within the casing, and
- 5 means, including an electric circuit to be closed at a point extraneous of the casing, to control engagement of said latching members.
3. A safety device for a machine of the
- 10 character set forth including: a connecting rod consisting of two members, an actuating device for one of said members, a casing carried by one of said members, a latch engaging member on the other of said members
- 15 to enter the casing, a complementary latching member, within the casing, consisting of a pair of jaws normally spread apart, and means extraneous of the casing to close the jaws against the latch engaging member.
- 20 4. A safety device for a machine of the character set forth including: a connecting rod consisting of two members, an actuating device for one of said members, a casing carried by one of said members, a latch engaging member on the other of said members
- 25 to enter the casing, a complementary latching member, within the casing, consisting of a pair of jaws normally spread apart, and means, including an electric circuit to
- 30 be closed at a point extraneous of the cas-

ing, to close the jaws against the latch engaging member.

5. A safety device for a machine of the character set forth including: a connecting rod consisting of two members, an actuating device for one of said members, a casing carried by one of said members, a latch engaging member on the other of said members to enter the casing, a complementary latching member within the casing, means extraneous of the casing to cause said latching members to engage, and a cam movable with one of the latching members to disengage them.

6. A safety device for a machine of the character set forth including: a connecting rod consisting of two members, an actuating device for one of said members, a casing carried by one of said members, a latch engaging member on the other of said members to enter the casing, a complementary latching member within the casing, means, including an electric circuit, to cause said latching members to engage, and a cam movable with one of the latching members to disengage them upon movement of the actuating means when the circuit is broken.

Signed at New York city, in the county of Bronx and State of New York, this 20th day of July, 1925.

JAMES B. MONAHAN.
